UNITED STATES PATENT OFFICE.

THEODORE SIMONSON, OF HILLSBOROUGH, OHIO.

HAND-RAIL FOR STAIRWAYS.

SPECIFICATION forming part of Letters Patent No. 287,968, dated November 6, 1883.

Application filed July 20, 1883. (No model.)

To all whom it may concern:

Be it known that I, THEODORE SIMONSON, of Hillsborough, in the county of Highland and State of Ohio, have invented certain new and useful Improvements in Hand-Rails for Stairways, of which the following is a full, clear, and exact description.

This invention relates to the hand-rails of open stairways, which heretofore have required twists or posts to extend in different directions.

The object of my invention is to provide certain new and useful improvements in the hand-rail, whereby the rail-sections can be united in a more convenient manner.

The invention consists in blocks or caps provided at each bend or angle of the hand-rail, against which blocks the ends of the rail-sections abut, whereby the sections of the rail can be united without requiring posts or the rail to be twisted or to have its cross-section changed.

Reference is to be had to the accompanying drawings, forming part of this specification, in which similar letters of reference indicate corresponding parts in both the figures.

Figures 1 and 2 are perspective views of the frames of stairways, the hand-railings of which are provided with my improvements.

In open staircases composed of several successive sections, each running in a different direction, the hand-rails cannot be united or cut to fit well at inclines or angles without materially changing the shape or size, which makes them very expensive.

I arrange the sections of the stair-rail A in such a manner that they run out at the same height, the risers of the stairway being arranged accordingly. Between the abutting ends of the rail-sections A, I place blocks or caps B, to which the ends of the rail-sections are secured, and which caps can be made more or less ornamental. No part of the hand-rail need be twisted, its section is not changed, less material is required, no posts are needed, and the cost of the stairway is reduced very much. The blocks or caps also give the hand-rail a

handsome finish, and permit of making open staircases in cheap houses, in which the ventilating open stairways have heretofore been replaced by the box or closed stairways, for which the railing could be provided more easily and at less expense than for an open stairway, in which the railing had to be twisted or a post provided in the usual way.

The above-mentioned caps or blocks are supported entirely by the rails, and as they are placed between the ends of the rail-sections they naturally unite them; but that is not their main function, but only a secondary matter.

The blocks B give the stairway, when finished, an appearance as if a post was provided at each turn, bend, or angle of the hand-rail, which effect is attained with less difficulty, labor, and expense than has heretofore been practicable.

I do not abandon or dedicate to the public any patentable feature set forth herein and not hereinafter claimed, but reserve the right to claim the same either in a reissue of any patent that may be granted upon this application or in any other applications for Letters Patent I may make.

Having thus fully described my invention, I claim as new and desire to secure by Letters Patent—

1. The combination, with the hand-rail sections of a stairway, of blocks or caps supported by the meeting ends of the sections of the rail, whereby the ends of the rail-sections can be finished and united without requiring them to be molded or shaped differently at the ends, substantially as herein shown and described.

2. A stairway-railing having a block or cap at each bend, angle, or turn, to which blocks or caps the ends of the rail-sections are fastened, the railing and blocks being supported by balusters, substantially as herein shown and described.

THEODORE SIMONSON.
